(57) **CLAIM**

I claim the ornamental design for a bottle, as shown and described.

DESCRIPTION

FIG. 1 is a perspective view of my new bottle;

FIG. 2 is an elevational view thereof;

FIG. 3 is a bottom view thereof; and,

FIG. 4 is a top view thereof.

The broken line showing of the cap in FIGS. 1, 2 and 4 is illustrative of environmental structure only and forms no part of the my claimed design.
